UNITED STATES PATENT OFFICE.

GERRIT VAN DAAM, OF BUFFALO, NEW YORK.

FUEL-SAVING DEVICE.

Application filed February 7, 1922. Serial No. 534,673.

To all whom it may concern:

Be it known that I, GERRIT VAN DAAM, a citizen of the United States, residing at Buffalo, in the county of Erie, State of New York, have invented a new and useful Fuel-Saving Device, of which the following is a specification.

The invention relates to improvements in fuel saving device. The object is to provide improved means for introducing into the combustion chamber, especially over the fuel bed, fresh air from outside the furnace, heated to a high temperature before its discharge over the fuel bed, so that said fresh air shall not chill or damp the fire, and so that the combustion of the gases rising from the fuel bed shall be more completely accomplished.

The special feature of the invention is the improved structures whereby a maximum efficiency is attained by a device occupying a minimum of space, and simple in construction.

By my improved means I am also able to vary the heating spaces and areas, between the intake and discharge, to suit different conditions.

Referring to the drawings which illustrate, merely by way of example, suitable means for effecting my invention:—

Fig. 1 is a view in perspective of a furnace with my improved device applied thereto.

Fig. 2 is a side elevation of the device on an enlarged scale.

Fig. 3 is a longitudinal vertical section of same.

Fig. 4 is a longitudinal vertical section of a modification.

Fig. 5 is a similar view of a single unit or section of a heating device made up of a plurality of units or sections.

Similar numerals refer to similar parts throughout the several views.

In its simplest form, my improved device for delivering heated air to the combustion chamber comprises two chambered bodies as shown in Figs. 1, 2 and 3. The chambered body 6 is semispherical in form having its flat wall 7 adapted to lie against the inner wall of the furnace, or the furnace door 8 as shown in Fig. 1. This inner wall 7 is provided with a central opening having an interior flange or collar 9. This opening is provided with an interior thread to cooperate with the thread of the air intake tube 10. This tube extends through the wall or door of the furnace and is preferably

held in place by the nut 11 and is provided at its outer end with a flaring mouth piece 12 having the usual damper 13 operated by means of the lug 14 or other suitable means. The inner end of tube 10 is also provided with the lock nut 15 for locking against the flange or collar 9. Upon the other side of chambered body 6 is provided the nozzle opening 16 interiorly threaded to cooperate with one end of the connecting pipe 17; the other end of said pipe may either be integral with, or threaded into, the chambered body 18, which in the present example, is shown as substantially spherical. The inner side of body 18 is provided with the discharge nozzle 19, which again may be integral therewith or threaded into the body 18 as shown. This nozzle 19 is provided with the discharge vents 20. Within the chambered bodies 6 and 18 are provided a plurality of pins or projections 21. In chamber 6 these projections are shown as extending toward the flat wall 7 of the chambered body; while in the chambered body 18 the pins 21 are shown as extending toward the axis of the chamber from all parts of the periphery thereof. Similar pins are also shown in the connecting pipe 17.

In operation: When the device is mounted as shown in Fig. 1 and the door 8 is closed, the damper 13 may be kept closed or nearly closed until the device becomes heated by the fire within the combustion chamber. As the heat communicated to the device increases, the amount of air permitted to pass through it may be correspondingly increased without danger of damping or checking the fire. The peculiar construction of chamber 6 with its semi-spherical wall toward the fire gives a maximum of heating area exposed to the fire. The projecting pins 21 increase the amount of heat communicated from the walls of chamber 6 to the air passing from pipe 10 to pipe 17. The air flowing into the chambered body 6 naturally becomes expanded by the heat communicated to it, and it is then to a certain degree compressed as it is drawn through the narrower channel of pipe 17. As the air passes through this pipe 17 in contact with the several projecting pins 21, further heat is absorbed. Passing into chambered body 18, the air is again expanded and further heated by the spherical walls of body 18 and the pins 21 extending inwardly therefrom. From this chamber

the air is drawn through the air discharge vents 20 into the combustion space above the fuel bed, for facilitating the complete combustion of the gases arising therefrom.

5 The peculiar formation of the semi-spherical body 6, and the spherical body 16, connected by the neck 17, presents a maximum of surface exposed to the heat of the fuel bed, so that by the combined means shown 10 a maximum quantity of air may be drawn through the device into the combustion chamber at a temperature sufficiently high to prevent any damping or chilling of the fire. As the parts can all be made separately and threaded together it forms an extremely simple and inexpensive structure to make and to repair.

In Fig. 6 is shown a modification which comprises the interposition between the 20 chambered bodies 6 and 18 of additional chambered bodies such as 22 and 23. These several chambered bodies may be of varying shapes as shown, depending upon the conditions under which the same are sought to be used. These several bodies are connected 25 by similar short pipes, such as 24 and 25. In these chambers 22 and 23, I have shown baffles such as 26 and 27. These baffles consist in substantially round flat plates of less 30 diameter, than that of the chambers. They are supported in any suitable way, as by rods 28 and 29, so that the air, passing from one connecting pipe, such as 17, to the next connecting pipe, such as 24, first strikes 35 the baffle 26 and is forced to pass around the margin thereof so that it will have closer contact with the surrounding walls of the chamber. In the modification shown in Fig. 40 4, I have shown the discharge vents around the periphery of the nozzle 19 as well as in its face.

In Fig. 5, I have shown a single unit or chamber 30 adapted to be connected up with other similar units. I have shown in this 45 unit a baffle 31 having slightly curved faces to facilitate the flow to the outer periphery thereof.

It will be obvious that with the arrangement indicated, it is possible to lengthen 50 or shorten the complete device by including

further chambered elements such as 22 and 23, or by eliminating one or more of them to suit the nature of the furnace or combustion chamber with which it is to be used, and thus it is possible to adapt the device 55 to almost any form of standard furnace.

What I claim is:

1. In a fuel saving device, the combination of two communicating chambered bodies having axes on the same horizontal 60 line, one of substantially semi-spherical formation, having a flat wall adapted to lie adjacent an inner wall of the furnace, and adapted to receive air from outside the furnace, the other of substantially spherical 65 formation adapted to discharge air into the combustion space of the furnace and a pipe formation threaded throughout its extent for connecting said chambered bodies, having fingers extending radially from its inner 70 wall.

2. In a fuel saving device, the combination of two communicating chambered bodies having axes on the same horizontal line, one of substantially semi-spherical formation, having a flat wall adapted to lie adjacent an inner wall of the furnace, and adapted to receive air from outside the furnace, the other of substantially spherical 75 formation adapted to discharge air into the combustion space of the furnace, said semi-spherical chamber having a plurality of substantially parallel tapered fingers projecting from its inner semi-spherical wall toward its flat wall.

3. In a fuel saving device, the combination of two communicating chambered bodies having axes on the same horizontal line, one of substantially semi-spherical formation, having a flat wall adapted to lie 80 adjacent an inner wall of the furnace, and adapted to receive air from outside the furnace, the other of substantially spherical formation adapted to discharge air into the combustion space of the furnace, said spherical chamber having a plurality of substantially parallel tapered fingers projecting from its inner wall at right angles to the 85 horizontal axis.

GERRIT VAN DAAM.
